CLAIM

The ornamental design for a folded box cover, substantially as shown and described.

DESCRIPTION

FIG. 1 is a plan view of a foldable box cover panel prior to being folded to form the cover.

FIG. 2 is a top plan view of a folded box cover showing my new design;

FIG. 3 is a side elevational view thereof, the other side view being similar;

FIG. 4 is a bottom plan view thereof; and,

FIG. 5 is an end view thereof;
